CLAIM

The ornamental design for a safety attachment for electrical outlet, as shown and described.

DESCRIPTION

FIG. 1 is a perspective view of a safety attachment for electrical outlet, showing my new design;

FIG. 2 is a top plan view thereof;

FIG. 3 is a bottom plan view thereof;

FIG. 4 is an elevational view of one end thereof, the opposite end view being a mirror image thereof;

FIG. 5 is an elevational view of one side thereof, the opposite side view being a mirror image thereof; and,

FIG. 6 is a transverse sectional view thereof, taken on the line 6—6 in FIG. 2 and showing the mounting plate overlying the oppositely directed feet projecting from the base of the plug shield.

The broken lines in FIG. 5 representing an electrical outlet cover plate, screw and outlet plug form no part of the design.
